REDUCING VALVE

Braxton L. Robart and Earl P. Buell, Jackson,
Mich., assignors to The Robuell Company, a
corporation

Application June 20, 1932, Serial No. 618,096

3 Claims. (Cl. 50—35)

This invention relates to an improvement in pressure reducing valves for fluids and has particular application in the reduction of steam or air pressure.

5 It becomes the primary object of this invention to provide a self regulating reducing valve which may be readily coupled to the high pressure side of a fluid pressure system of uniform or fluctuating pressure and deliver substantially uniform predetermined low pressure.

More specifically stated, one of the objects of this invention is to provide a reducing valve having a slideable piston valve transversely balanced throughout its length to minimize wear and friction and longitudinally balanced by the low pressure to regulate the same.

Another object of this invention is to provide a reducing valve which is automatic in its action yet is constructed of simple cast sections necessitating but little machining.

Other objects and advantages of our invention will appear as the description of the invention proceeds. It is to be clearly understood, however, that we do not intend to limit ourselves to the exact details shown or described but that we intend to include as part of our invention, all such changes and modifications of parts as would occur to those skilled in this art and would fall within the scope of the claims.

30 In the drawing where a longitudinal cross sectional view of one form that this invention may take is shown, reference character 1 generally designates a pressure reducing valve comprising a central sleeve member 2 having flanged ends 3. Upper and lower housings 4 and 5, having flanges 6 and 7, respectively, are secured to the central sleeve member 2 by any well known securing means, for example, by bolts 8 passed through the respective flanges. The sleeve 2 is provided 35 with a circumambient jacket chamber 9 opening into a flanged chamber 10 constituting an inlet port. A port 11 is provided in the sleeve 2 opening into the chamber 9. The port 11 may take any number of forms but it is preferably constructed 40 as an annular slot extending entirely around the sleeve 2 as illustrated.

A piston valve 12 is slidably arranged within the sleeve 2 and extends downwardly into the chamber 5 and is guided at the lower end in an auxiliary sleeve 13 cast within the chamber 5 and defining a port 14, similar to the port 11, between its upper end and the lower end of the sleeve 2. Ports 15 and 16 are arranged in the piston valve 12 intermediate the ends and are spaced a distance equal that between the ports 11 and 14. Al-

though our invention is not limited to any particular type, the ports 15 and 16 are preferably positioned at an angle with the longitudinal axis of the piston valve 12 to shorten the travel of the valve necessary to close the ports.

5 A cap 17, having an annular shoulder 18, is secured to the upper end of the piston valve 12 and an inverted cup-shape member 19 with a flanged edge 20 is secured to the lower end by a bracing rod 21 extended through apertures in 10 the cap 17 and the member 19. The ends of the rod 21 are threaded and nuts 22 are drawn up to clamp the cap 17 and the member 19 to the ends of the piston valve 12.

A circular grooved spring seat 23 is supported 15 on the cap 17 and in turn supports a spring 24 located within the chamber 4. The upper portion of the chamber 4 is provided with a tapped boss 25 into which an adjustment screw 26 is threaded. As illustrated, the end of the screw 26 20 is positioned in a well 27 in an upper spring seat 28 and is adapted to place the spring 24 under compression to force the piston valve 12 downwardly until the end of the rod 21 contacts with the stop 29 tapped in the plug 31.

25 The operation of above described mechanism is as follows: Steam or the like under high pressure is admitted through the inlet port 10 and fills the jacket chamber 9 surrounding the sleeve 2. Under initial conditions, the spring 24 will 30 force the piston valve 12 downwardly to the position shown in the drawing with the restricted ports 15 in the horizontal plane of the port 11 in the sleeve 2. In this position the fluid pressure will flow through the ports 11 and 15 and 35 will expand in the interior of the piston valve 12. When the ports 11 and 15 are in communication, the ports 14 and 16 are likewise positioned, and the expanded fluid will flow through the restricted ports into the chamber 29 constituting 40 an outlet port on the low pressure side of the valve when the fluid is again expanded to further reduce the pressure. In actual operation there is invariably present a fluctuating high pressure resulting from irregularity at the source as well 45 as a fluctuating low pressure resulting from intermittent consumption or fluctuation of the high pressure. As it is advantageous to maintain a substantially constant low or output pressure, the pressure in the chamber 29 is maintained 50 substantially constant in the following manner independent of the rate of consumption or fluctuation of the high pressure: As the pressure builds up in the chamber 29, at a predetermined pressure, depending upon the adjustment of the 55

screw 26, a back pressure admitted through a plurality of ports 30 located in the auxiliary sleeve 13 will act against the cup-shaped member 19 to force the piston valve 12 upwardly to partially or perhaps to completely close the ports 15 and 16. It will be readily apparent that as the ports 15 and 16 are further restricted less fluid will be admitted therethrough and the reducing of the pressure will be greater with the result that the piston valve 12 will float between the tension of the spring 24 and the upward pressure against the member 19 to automatically maintain substantially a constant low pressure in the chamber 29.

15 Obviously the weight of the piston valve or additional weights may be employed in lieu of the spring 24 to force the piston downwardly. Likewise, we do not wish to limit the invention to any particular shape of the member 19 as any 20 surface which will transmit an upward pressure from the low pressure side of the reducing valve against the piston valve 12 may be employed. The dominant feature of our reducing valve resides in transversely balancing a piston valve 25 in a sleeve while floating the piston longitudinally between a uniform downwardly directed force and the upwardly directed force of the back pressure on the low pressure side of the valve.

Having described our invention what we claim 30 as new and desire to protect by Letters Patent is:

1. A fluid pressure regulator comprising a vertical cylindrical sleeve having a flange spaced from the lower end thereof, a horizontal high pressure inlet connection jacketing said sleeve, 35 a housing constituting a horizontal low pressure outlet connection having a flanged portion telescoping with the lower end of said sleeve and removably secured to said first flange, an auxiliary cylindrical sleeve concentric with said first sleeve and located within and spaced from said housing at the sides and from said first sleeve at the upper end to provide a port, a port in said first sleeve opening into said first jacket, a longitudinally ported hollow piston valve closed at both 40 ends slidably disposed in said sleeves for regulating communication between said inlet and out-

let, a by-pass directing low pressure into said auxiliary sleeve against the piston valve end slidable therein to move the same in one direction, and regulable means for moving said valve in the opposite direction.

2. A fluid pressure regulator comprising a vertical cylindrical sleeve having a flanged portion at the lower end, a horizontal high pressure inlet connection jacketing said sleeve, a housing constituting a horizontal low pressure outlet connection having a flanged portion removably secured to said first flange, an auxiliary cylindrical sleeve concentric with said first sleeve and located within and spaced from said housing at the sides and from said first sleeve at the upper end to provide a port, a port in said first sleeve opening into said first jacket, a longitudinally ported hollow piston valve closed at both ends slidably disposed in said sleeves for regulating communication between said inlet and outlet, a by-pass directing low pressure into said auxiliary sleeve against the piston valve end slidable therein to move the same in one direction, and regulable means for moving said valve in the opposite direction.

3. A fluid pressure regulator comprising a vertical cylindrical sleeve, a horizontal high pressure inlet connection jacketing said sleeve, a housing constituting a horizontal low pressure inlet connection connected to said vertical cylindrical sleeve, an auxiliary cylindrical sleeve concentric with said first sleeve and located within and spaced from said housing at the sides and from said first sleeve at the upper end to provide a port, a port in said first sleeve opening into said first jacket, a longitudinally ported hollow piston valve closed at both ends slidably disposed in said sleeves for regulating communication between said inlet and outlet, a by-pass directing low pressure into said auxiliary sleeve against the piston valve end slidable therein to move the same in one direction, and regulable means for moving said valve in the opposite direction.
